UNITED STATES PATENT OFFICE.

WARD DE WITT LAMB, OF LE MARS, IOWA.

CAN OPENER.

Application filed January 6, 1926. Serial No. 79,582.

The present invention has reference to can openers and aims to provide a can opener especially designed for opening a can by cutting the can at a point adjacent to either 5 end thereof.

An important object of the invention is to provide an opener of this character so constructed that all danger of the operator cutting his hand by the opener slipping 10 while in use, is eliminated.

A further object of the invention is to provide a can opener which may be adjusted, thereby adapting the same for use in 15 opening cans of various diameters.

15 The can may be opened, by the invention, so that the contents may be removed therefrom without breaking or tearing them.

With the foregoing and other objects in view which will appear as the description 20 proceeds, the invention resides in the combination and arrangement of parts and in the details of construction hereinafter described and claimed, it being understood that changes in the precise embodiment of the 25 invention herein disclosed, may be made within the scope of what is claimed, without departing from the spirit of the invention.

Referring to the drawing:

30 Figure 1 is a bottom plan view of a can opener constructed in accordance with the invention.

Figure 2 is a side elevational view thereof.

Figure 3 is a sectional view taken on line 35 3-3 of Figure 1.

Referring to the drawing in detail, the device includes an elongated body portion indicated by the reference character 5 which is formed with a downwardly extended end portion 6, to which the prong 7 is secured, the prong being constructed so that it will 40 extend forwardly for purposes to be hereinafter more fully described.

Forming a part of the can opener is a 45 carriage made of one or more parts indicated generally by the reference character 8 which carriage includes a plate having upstanding portions 9 formed with openings to accommodate the body portion 5, the upstanding portions 9 being disposed adjacent to the ends of the body portion as clearly shown by Figure 2 of the drawing.

50 Downwardly extended flanges 10 are also formed on the body portion, and between 55 which the knife supporting bar 11 is mounted. Mounted in the flanges 10 are spaced

pins 12 which have upwardly extended pins 13 which are secured to the plate. The bar 11 is formed with elongated openings 14 for the reception of the pins 13, whereby the 60 bar 11 is mounted for sliding movement between the flanges 10.

At the forward end of the bar 11 is a cutting member, knife, blade or disk 14' which is adapted to engage the can being 65 opened at a point adjacent to the upper edge thereof, to cut the upper portion of the can and permit it to be lifted.

A head 15 is formed at one end of the bar 11 and acts as a stop for one end of the 70 coiled spring 16 which has its opposite end bearing against one of the pins or head-bolts 13 as shown by Figure 2.

Co-operating with the head 15 is an offset 75 enlargement 17 formed at the forward end of the lever 18 which is pivotally supported between the flanges 10 on the pivot pin 19.

As shown, this lever is disposed directly under the handle portion 20 of the body portion 5 so that the operator may by grasping 80 the handle portion and lever 18 and gripping the lever 18, move the bar 11 forwardly until the cutter 14' contacts with the can.

Formed integral with the body portion 85 are spaced depending flanges 21 that are adapted to fit over the usual head formed at the ends of a can so that the carriages will be held against movement longitudinally of the body portion 5, when pressure is brought 90 to bear on the lever 18 to move the cutter 14 into engagement with the can.

When the prong 7 has been properly positioned within the end of the can and the flanges 21 have been positioned within the 95 end of the can and the flanges 21 have been positioned over the head in a manner as described, it will be obvious that when the cutter 14' is moved into close engagement with the can and the body portion is rotated, 100 the can will be cut adjacent to the cap thereof of removing a portion of the can to open the same.

I claim:

A can opener including an elongated body 105 portion having a prong, a carriage including a length of sheet metal having lateral parallel flanges and having right angled end portions formed with openings to permit the carriage to be positioned on the body portion, pins connecting the lateral flanges, 110 pins connected with the first mentioned pins

and extending through the carriage, a knife supporting bar having a knife at one end and having elongated openings to accommodate the last mentioned pins to guide the knife supporting bar, a coiled spring for normally urging the knife supporting bar rearwardly, a lever pivotally mounted between the laterally extended flanges, said lever having an offset enlargement at one

end, said offset enlargement adapted to engage one end of the knife supporting bar, and said enlargement adapted to move the knife supporting bar forwardly when the lever is pressed towards the body portion.

In testimony that I claim the foregoing as my own, I have hereto affixed my signature.

WARD DE WITT LAMB.
